UNITED STATES PATENT OFFICE.

BOLESLAW PUCILOSKI, OF CHICAGO, ILLINOIS.

DESIGN FOR A CUFF-BUTTON.

48,987.

Specification for Design.

Patented May 2, 1916.

Application filed January 21, 1916. Serial No. 73,477. Term of patent 7 years.

To all whom it may concern:

Be it known that I, BOLESLAW PUCILOSKI, a subject of the Czar of Russia, residing at Chicago, in the county of Cook and State of Illinois, have invented a new, original, and ornamental Design for a Cuff-Button, of which the following is a specification, reference being had to the accompanying drawing, forming part thereof.

Figure 1 is a side elevation of a cuff button showing my design. Fig. 2 is a front elevation of the enlarged head end thereof, and, Fig. 3 is a similar view of the relatively small base end of the same.

I claim:—

The ornamental design for a cuff button, as shown.

BOLESLAW PUCILOSKI.
